US0D1042523S

(12) **United States Design Patent** (10) Patent No.: **US D1,042,523 S**
(45) Date of Patent: ** Sep. 17, 2024

(54) **DISPLAY SCREEN OR PORTION THEREOF WITH GRAPHICAL USER INTERFACE**

- (71) Applicant: **Apple Inc.**, Cupertino, CA (US)
(72) Inventors: **Imran Chaudhri**, San Francisco, CA (US); **Raymond Sepulveda**, Portland, OR (US)
(73) Assignee: **Apple Inc.**, Cupertino, CA (US)
(**) Term: **15 Years**
(21) Appl. No.: **29/856,031**
(22) Filed: **Oct. 10, 2022**

Related U.S. Application Data

- (63) Continuation of application No. 29/824,289, filed on Jan. 24, 2022, now Pat. No. Des. 966,327, which is a continuation of application No. 29/769,565, filed on Feb. 5, 2021, now Pat. No. Des. 941,870, which is a continuation of application No. 29/687,727, filed on Apr. 15, 2019, now Pat. No. Des. 910,053, which is a continuation of application No. 29/619,368, filed on Sep. 28, 2017, now Pat. No. Des. 845,981, which is a continuation of application No. 29/492,619, filed on Jun. 1, 2014, now abandoned.

CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface.

The broken lines around the FIGURE show a display screen or portion thereof, and form no part of the claimed design.
